LOUIS WILLIAM KLEIN, OF CHICAGO, ILLINOIS, ASSIGNEE TO INTERNATIONAL COMBUSTION ENGINEERING CORPORATION, OF NEW YORK, N. Y., A CORPORATION OF DELAWARE.

TRAVELING-GRAVE STOKER.

Application filed January 27, 1925. Serial No. 4,891.

My invention relates to stokers, and has special reference to chain grate stokers of the type in which the upper run of the grate rides upon a supporting structure comprising 5 a plurality of beams arranged between and extending transversely of the runs of the grate and supported at their ends by the side walls of the furnace. The transverse beams cooperate with other parts of the structure 10 to form a plurality of transversely extending compartments for receiving ashes and other siftings from the grate and for supplying air to the fuel bed, the several compartments being in communication with separate sources 15 of compressed air supply. Heretofore, particularly in the case of relatively wide chain grate stokers, considerable difficulty has been experienced with the beams sagging at their centers which is due to the weight of the upper 20 run of the grate and the material supported thereon, and also to the heat of the burning fuel particularly when the fire is banked. Such sagging of the beams is objectionable as it results in an unevenness of 25 the fuel bed, and injury to the grate, and causes gaps between the chain grate and the supporting structure which destroys the air seal between the several compartments.

An object of the present invention is to 30 provide a traveling grate stoker of the character indicated in which there is provision of means for obviating the objectionable feature of the prior construction above described.

Another object of the invention is to provide a novel and improved traveling grate stoker.

The several features of the invention, whereby the above mentioned and other objects may be attained, will be clearly understood from the following description and accompanying drawings, in which:

Figure 1 is a longitudinal sectional view, partly shown diagrammatically of a chain grate stoker embodying the features of the invention in their preferred form, the section being taken substantially on the line 1—1 of Fig. 2; and

Fig. 2 is a transverse sectional view taken substantially on the line 2—2 of Fig. 1.

The stoker illustrated in the drawings is provided with an endless chain grate 2 which

passes over a sprocket wheel 4 and a drum 6 arranged at the front and rear ends thereof and mounted on shafts 8 which extend between the longitudinal side walls 10 of the stoker. The stoker is further provided with a supporting structure upon which the upper run of the grate rides and which is arranged between and extends transversely 55 of the upper and lower runs of the grate. This supporting structure is provided with a plurality of transversely extending compartments for receiving ashes and other siftings from the upper run of the grate and for supplying air under pressure to the fuel bed, the air supply to the different compartments being independently controlled. As shown, this structure comprises a plurality of transversely extending I-beams 12 which extend 60 between and are supported by the longitudinal side walls of the stoker. A plurality of longitudinally extending rails 14 upon which the upper run of the grate rides are supported upon the I-beams, and sealing plates or 65 bars 15 are also mounted upon the I-beams and extend between the rails. The ash receiving and air supplying compartments are each formed by walls 16 that are arranged 70 transversely in V-form and have their upper edges secured to the upper portions of the I-beams of each pair, any suitable means being provided for removing the ashes accumulating in each compartment and for supplying air under pressure to the compartments independently of each other. The parts above 75 described are of a well known construction.

In the illustrated construction means is provided for obviating any danger of the I-beams sagging under the weight of the upper run of the grate and the material supported thereon. To provide for this the several I-beams 12 are centrally supported by a heavy I-beam 18 which extends centrally of the grate and is mounted upon suitably arranged cement pillars 20. The I-beams 12 are rigidly secured on the beam 18 as by bolts 19. In order that the I-beam 18 shall not interfere with the chain grate, the latter is divided longitudinally into two sections, 90 the lower runs of the two sections being arranged at opposite sides of the central web of the I-beam 18 so as to clear it. In order to prevent coal and ashes from working down 95 100

into the resulting space between the upper runs of the grate sections, a strip 22 of iron or steel is inserted between the runs and supported upon the transverse sealing plates 15.

5 The strip of steel 22 is of suitable width or height to position its top surface in the plane of the top surface of the grate and is held from movement on the sealing plates 15 in a suitable manner as by pins 24.

10 It will be apparent that the I-beam 18 and its supporting pillars provide a firm and rigid support for the center of the transverse I-beams 12, and that as the parts are bolted together the beam acts as a stiffener for the whole supporting structure.

15 As will be evident to those skilled in the art, my invention permits various modifications without departing from the spirit thereof or the scope of the appended claims.

20 What I claim is:

1. A stoker of the class described having, in combination, an endless traveling grate divided longitudinally into two sections arranged side by side and spaced a slight distance apart so as to form a fuel supporting and propelling surface substantially continuous throughout its width, a supporting structure to prevent sagging of the upper run of the grate arranged between the upper and 25 lower runs of the grate and over which the upper run passes, an I-beam extending longitudinally of the grate with its web extending through the space between the lower runs of

said sections and upon which said supporting structure is mounted, means for closing 35 the space between the upper runs of said sections throughout substantially the length thereof, and pillars upon which said I-beam is mounted, the space between said sections being only sufficient to permit the sections 40 to clear the web of the I-beam.

2. A stoker of the class described having, in combination, an endless traveling grate divided longitudinally into sections arranged side by side and spaced a slight distance apart 45 so as to form a fuel supporting and propelling surface substantially continuous throughout its width, a supporting structure to prevent sagging of the upper run of the grate arranged between the upper and lower runs of the grate and over which the upper run passes, an I-beam extending longitudinally of the 50 grate with its web extending through the space between the lower runs of said sections and upon which said supporting structure is mounted, and a strip 55 removably mounted upon said supporting structure and substantially closing the space between the upper runs of said sections throughout substantially the length thereof and having its top surface 60 in substantially the plane of the top surface of the grate.

In testimony whereof, I have signed my name to this specification this 23rd day of January, 1925.

LOUIS WILLIAM KLEIN.
